(57) **CLAIM**

The ornamental design for a mounting bracket, as shown and described.

DESCRIPTION

FIG. 1 is an isometric view of the mounting bracket according to the present application.

FIG. 2 is a front view of the mounting bracket.

FIG. 3 is a back view of the mounting bracket.

FIG. 4 is a left view of the mounting bracket

FIG. 5 is a right view of the mounting bracket.

FIG. 6 is a top view of the mounting bracket; and,

FIG. 7 is a bottom view of the mounting bracket.

The broken lines in the drawings illustrate portions of the mounting bracket which form no part of the claimed design.
